UNITED STATES PATENT OFFICE.

BURDETTE DUDLEY LA FORCE, OF OTTUMWA, IOWA.

HEMOSTATIC TONSILLOTOME.

1,097,132.

Specification of Letters Patent.

Patented May 19, 1914.

Application filed December 29, 1913. Serial No. 809,212.

To all whom it may concern:

Be it known that I, BURDETTE DUDLEY LA FORCE, citizen of the United States, residing at Ottumwa, in the county of Wapello and 5 State of Iowa, have invented certain new and useful Improvements in Hemostatic Tonsillotomes, of which the following is a specification.

This invention relates to improvements in 10 surgical instruments of the type called tonsillotomes, the primary purpose of which is to effect the removal of tonsils, adenoid growths, and other more or less inaccessible members or tissues.

15 While the instrument hereinafter described is especially designed for removing the faucial tonsils, the principles entering into its construction and operation are such that it may be effectively used for other surgical operations which requires ligation, 20 hemostasia and amputation, in rapid sequence, for their successful completion.

The especial object of the improvements which form the subject matter of this application, is to provide an instrument of the 25 type stated, in which a ligator, hemostat and knife are so combined that they may be conveniently and effectively operated in rapid sequence, as compared with separate instruments, thus requiring the patient to be under anesthesia for the briefest possible period, and by which a bloodless operation may 30 be performed.

A further object of my improvements is 35 to so combine the several instrumentalities which make up the complete device, that each will complement the other in effecting the various steps required in a complete operation upon the part removed.

40 A still further object of my improvements is to provide an instrument having its members of strong and simple construction, so assembled that they may be readily disassembled for cleaning, and in which there 45 will be no inaccessible joints or crevices.

Having the foregoing special objects, and others of general utility in mind, I have invented and designed the instrument herein shown, described and claimed in a preferred 50 form, as follows:—

In the accompanying drawing:—Figure 1 is a side elevation, in full size, of a faucial hemostatic tonsillotome constructed according to my invention; Fig. 2 is a top plan view of the instrument shown in Fig. 1; Fig. 3 is an enlarged sectional view of the

tonsil engaging terminals of the ligator, hemostat and knife of my improved instrument; Fig. 4 is an enlarged plan view of the rear portion of the main frame of my 60 improved tonsillotome; Fig. 5 is a top plan view of the knife member; Fig. 6 is a plan view of the hemostat; Fig. 7 is a plan view of the ligator; Fig. 8 is a fragmental view showing in elevation the upper portions of 65 the handle members of my invention, and— Fig. 9 is a detail of a spring catch which forms a feature of my invention.

Referring to the details of the drawing, the reference character 10 represents the 70 handle member of my improved instrument, and it is made up of the following parts:— A rearward grasping portion 10^a, a forward grasping portion 10^b, to the inner opposed faces of which are secured springs 10^c 75 adapted to force said grasping portions apart, as shown in Fig. 1. The handles are pivoted together at 10^d, and above their pivoted points are formed with integral extensions 10^d, 10^e, respectively, the former serving as a lever adapted to operate certain 80 other members of the instrument, and the latter or part 10^e, which is bifurcated having rectangular portions 10^f at its upper end, one of which is adapted to fit a correspond- 85 ing notch 11^a in the main frame of the instrument, to be hereinafter described. The terminals 10^f have a threaded hole 10^g formed therein, and the lever 10^d has a curved notch 10ⁱ formed in its inner edge as 90 shown in Fig. 8. The member 10^e is split, as indicated by dotted lines in Fig. 8, to receive the member 10^d when the latter is in its closed position, so that while one of the parts 10^f engages the notch 11^a in the frame 95 11, the other portion 10^f, passes through a suitable slot 11^b at the other side of the frame, as shown in Fig. 2. A thumb screw 10^g has a threaded engagement with the holes 10^g in the portions 10^f, and by tighten- 100 ing said nut the two terminals 10^f of the fork 10^e are removably but firmly clamped upon the frame of the instrument. The notch 10ⁱ in the inner edge of the member 10^d provides for the screw 10^g when the two 105 members 10^d, 10^e, are in their closed position.

11 represents generally the main frame of my improved instrument upon which the operating members are slidably mounted. This frame throughout the greater part of 110 its length is substantially a flat bar of steel, but at its rear portion is bent at right angles

to provide a post 11^a, the end of which is perforated to provide spaced threaded eyes 11^b. The bar is also bent at 11^c so that the portions 11^a, 11^c, and the connecting portion of the bar, form an open rectangular yoke, as clearly shown in Fig. 1. One edge of the bar adjacent the bend 11^c is cut away to provide the rectangular notch 11^d. The bar is further provided with a small diamond shaped slot 11ⁱ, a slot 11^j near the edge, opposite the notch 11^d, and an elongated slot 11^k extending longitudinally of the bar between the slot 11ⁱ and the notch 11^d. The forward end of the bar is formed 10 into a rectangular yoke 11^e, in the inner walls of which are slideways 11^f, 11^g, and the cross bar at the end of the yoke is slit to provide a passageway 11^h (see Fig. 3) for the knife 12.

20 The reference character 12 represents the knife member of my improved instrument, the same consisting of a thin steel bar, flat throughout the greater part of its length as shown in Fig. 5, but provided at its rear end 25 with a lug 12^a at right angles to the bar, through which lug is an opening 12^b. The bar is also provided with two slots 12^d, 12^e, extending longitudinally thereof, and at its forward end the bar is widened and provided with a beveled cutting edge 12^f. The knife rests upon the frame 11 and is mounted to slide in the groove 11^g in said frame.

As best shown in Fig. 6, the hemostat member, 13, of my improved instrument consists of a flat bar of steel except for the threaded stem 13^a, which extends rearwardly from the rear end of the bar. There are two longitudinal slots 13^b, 13^c, in said bar, and along one edge are ratchet teeth 13^d. 35 Near the forward end of the bar, and on the upper surface, are small guide lugs 13^e, and the forward end portion of the bar is widened and provided on its edges with flanges 13^f, adapted to engage the grooves or 40 slideway 11ⁱ in the frame 11. The forward end of the hemostatic bar is provided with serrations or teeth 13^g which are adapted to coöperate with similar teeth formed on the opposed edge of the yoke 11^e in the gripping 45 50 or crushing of the tonsil.

The ligator member, 14, or ligature carrier, of my improved instrument is shown in plan view in Fig. 7, and same consists of a thin flat bar throughout the greater portion of its 55 length, but at its rear portion is provided with a triangular shaped lug 14^a, which serves as a suitable finger-engaging portion of this member, its surface being preferably roughened to prevent slippage of the fingers 60 of the operator. This member 14, is also provided with an elongated slot 14^b, and its forward end is made tapering and somewhat thinner than the body of the member, and is rounded as at 14^c, and in the extreme end 65 of the rounded portion is a groove 14^d which

is adapted to receive the ligature 14^e, the ends of which are held by the spring clip 14^f, which is secured at one side of the lug 14^a by the screws 14^g, until the ligator has pierced the pedicle of the tonsil being operated on. 70

As shown in Figs. 1 and 9, the reference character 15 represents a spring latch, near one end of which is a post 15^a which terminates at its free end in a transverse tongue 15^b. The opposite end of the latch is formed with spreading angular extensions 15^c which are adapted to embrace the lower edge and sides of the bar 11 when the latch is in operative position, and when in this 80 position, the post or stem 15^a will pass through the slots 11ⁱ, 12^d, and 13^c, and the diamond shaped end 15^b of the stem will extend crosswise of the diamond shaped slot 11ⁱ. When it is desired to discharge the 85 catch; the end 15^b is forced downwardly against the tension exerted by the opposite end and the catch is given a quarter turn, thus bringing the end 15^b into registry with the slot 11ⁱ, so that it can be drawn through 90 the slot. As best shown in Fig. 2, a thumb screw 16 has a threaded engagement with the eyes 11^b at the rear end of the frame 11, and serves to guide the stem 13^a which passes below said screw. 95

Mounted upon the threaded stem 13^a, is a wheel 17 which, when screwed by turning to the left to the point shown in Fig. 1, in which it impinges against the end of the arm 11^a, serves as a lock-nut against the longitudinal movement of said stem when the forward end of the hemostat is in its most forward position, but when a longitudinal movement of the hemostatic member or bar of which said threaded stem is an extension 105 independently of the handle is desired, such movement is effected by the rotation of said nut 17 to the left and it also forces forward the knife, by reason of the connection between the rear end of the knife and stem 13^a, 110 which is effected by the hub extension 18^a on the nut 18. When it is desired to move the knife independently of the hemostat and the handle lever, the nut 18 is turned to the right or left, depending upon whether it is 115 desired to feed the knife forward or backward.

The reference character 19, represents a pawl pivotally mounted on a pin 20 in the frame 11, and adapted to have its point 19^a 120 held in operative engagement with the teeth 11ⁱ of the hemostat by the expansive action of a spring 21, when said hemostat is in position that will bring said point in the path of said teeth. The handle extension arm or lever 10^a engages the slots 11^k, 12^e, 13^b, and 14^b, and serves to push forwardly the knife and hemostat a certain distance when the handle members 10^a, 10^b, are brought close together by the operator. When thus oper- 125 130

- ated the pawl 19, by engaging the teeth 13^a will hold the parts in such position until the pawl is manually released.
- The method of procedure in the use of the hemostatic tonsillotome is as follows:—The faucial tonsil is engaged into the fenestrum of the instrument by placing the yoke 11^a around it and all of the tissues immediately in apposition to the capsule of the tonsil are thoroughly crushed by pressing the handles of the instrument tightly together, thus bringing the hemostat in close engagement with the tissues immediately back of the capsule, in which position it is held by the engagement of the pivotal pawl with the teeth provided therefor on the edge of the rear portion of the hemostat bar. The next step to further crush the tissues and clamp them effectively in the hemostat 20 yoke, is accomplished by turning the wheel 17 to the left, so that it will impinge against the end 11^a of the main frame. After the tissues are thoroughly crushed, the ligator or ligature carrier, with a ligature looped over the end 14^a, and in the groove 14^a, and held under tension by the spring catch 14^a, is pushed forwardly, piercing the tissues clamped by the hemostat. Whereupon the ligature is slackened by disengaging it 30 from the catch, the ligator retracted, thus leaving the loop end of the ligature on the farther side of the tissues, where it may be grasped by suitable instruments, the loop brought around the rear end of the instrument and the ligation completed by tying the ligature down tightly against the tissues under compression. This ligation operation may be repeated in as many places as the size of the member operated upon 40 may require. After these operations are performed, the operating nut 18 is turned to the right thereby sliding the knife through the groove provided therefor in the frame, and severing the tonsil or part operated upon immediately adjacent the hemostat. The hemostat is then released by turning the nut 17 to the right and releasing the pawl 19, thereby allowing the springs 10^a to expand the handles, and retracting the knife and hemostat. The several operations described effect the complete enucleation of the tonsil without hemorrhage.
- I claim:—
1. A surgical instrument comprising a fixed frame having a fenestrum at its forward end, a pair of handles detachably connected with said frame, one of said handles being pivotally connected with the other and having an arm extending through said frame, a hemostat bar slidably arranged on said frame, a knife slidable on said frame, and a ligator slidably on said hemostat bar, said bar and knife adapted to be operated by said arm and to enter said yoke.
2. A surgical instrument comprising a fixed frame having a fenestrum at its forward end, a pair of handles detachably connected with said frame, one of said handles being pivotally connected with the other and having an arm extending through said frame, a hemostat bar slidably arranged on said frame, a knife slidable on said frame adjacent said bar, a ligator slidable on said hemostat bar, said bar and knife adapted to be operated by said arm and to enter said yoke, and means for locking said bar in operative position.
3. A surgical instrument comprising a fixed frame having a fenestrum at its forward end, a pair of handles connected with said frame, one of said handles being pivoted to the other and having an arm extending through said frame, a hemostat bar slidably mounted on said frame and having a slot operatively engaged by said arm, a knife slidably mounted on said frame and having a slot operatively engaged by said arm, means for locking said bar in operative position, and means for detachably connecting said bar and knife with said frame.
4. A surgical instrument comprising a frame having a fenestrum at its forward end, a pair of handles connected with said frame, a hemostat bar slidably mounted on said frame, and adapted to enter said fenestrum, a knife slidably mounted on said frame, means for operating said bar and knife, means for locking said bar in operative position, and means for detachably connecting said bar and knife with said frame.
5. A surgical instrument, a frame having a fenestrum at its forward end, a pair of handles connected with said frame, a hemostat bar slidably mounted on said frame, and adapted to enter said fenestrum, means for operating said bar from said handles and independent means for further operating said bar, a knife slidably mounted on said frame, and means for operating said knife.
6. In a surgical instrument, a frame having a fenestrum at its forward end, a hemostat bar slidably mounted on said frame and adapted to enter said fenestrum, a ligator slidably arranged on said hemostat, means for operating said hemostat and means for operating said ligator.
7. In a surgical instrument, a frame, a hemostat slideable on said frame and adapted to coöperate therewith in crushing the part to be operated on, a ligator slideable on said hemostat, means for operating said ligator, means for holding a ligature under tension on said ligator, means for operating said hemostat, and means for locking said hemostat in operative position.
8. In a surgical instrument, a supporting

member, a hemostat, a ligator and a knife, slidably arranged in superposed relation on said frame, independent means for operating said hemostat, ligator and knife, and 5 means for locking the hemostat in operative position.

In testimony whereof I affix my signature in the presence of two witnesses.

BURDETTE DUDLEY LA FORCE.
